FLUID PRESSURE ACTUATED HORN UNIT

Alexis De Sakhnoffsky, Grand Rapids, Mich., assignor
to The Hadley Manufacturing Company, Toledo, Ohio,
a corporation of Ohio

Application July 23, 1958, Serial No. 51,903

Term of patent 14 years

(Cl. D72—1)

Figure 1 is a top plan view of a fluid pressure actuated horn unit showing my new design;

Fig. 2 is a side elevational view thereof;

Fig. 3 is a rear view on a slightly enlarged scale thereof;

Fig. 4 is a front view on a slightly enlarged scale;

Fig. 5 is a sectional view of the horn unit taken along the line 5—5 in Fig. 4, looking upward in the direction of the arrows.

The essential features of the design are shown in full lines.

I claim:

The ornamental design for a fluid pressure actuated horn unit, substantially as shown and described.
